UNITED STATES PATENT OFFICE.

ARNOLD STUCKI, OF ALLEGHENY, PENNSYLVANIA, ASSIGNOR TO PRESSED STEEL CAR COMPANY, OF PITTSBURG, PENNSYLVANIA, A CORPORATION OF NEW JERSEY.

ORE-CAR.

SPECIFICATION forming part of Letters Patent No. 731,242, dated June 16, 1903.

Application filed June 28, 1902. Serial No. 113,677. (No model.)

To all whom it may concern:

Be it known that I, ARNOLD STUCKI, a citizen of the United States, residing at Allegheny, in the county of Allegheny and State of Pennsylvania, have invented a certain new and useful Improvement in Ore-Cars, of which the following is a full, clear, and exact description.

The object of this invention is to provide a side-dump car for transporting ore and other material.

In carrying out the invention I provide a body which in general profile may be likened to an inverted pyramid, the base of which has vertical sides, and this body is mounted upon an underframe composed, essentially, of center sills constructed with bolsters and having ends whose sides converge from the bolsters to the draft-rigging sills. The sides are provided with outwardly and downwardly opening doors for the discharge of the load and arranged so that the whole load can be dumped either to one side of the car or the other. The operating mechanism for these doors extends to the ends of the car. Rests are provided to support the doors in their opened positions in order to convert them into chutes for the load. Since side sills are done away with and the sides must carry the load, these sides are reinforced internally and externally by gusset-plates. These features of construction, together with others, as hereinafter more particularly specified and claimed, constitute the invention.

In the accompanying drawings, illustrating my invention, in the several figures of which like parts are similarly designated, Figure 1 is a half vertical section taken through one of the doors or gates and an end view. Fig. 2 shows in its left-hand half a plan view just above the underframe, while it shows in its right-hand half a top plan view of the body and end. Fig. 3 shows in its left-hand half a vertical longitudinal section and in its right-hand half a side elevation.

The underframe comprises, essentially, a pair of center sills 1, which are herein shown as extending from end to end of the car and as constituting not only the center sills proper,

but also the draft-rigging sills and bolsters 50 at their opposite ends, and, as herein shown, these bolsters comprise pairs of diaphragms 2, riveted to opposite sides of the center sills, and a pair of diaphragms 3, riveted between the said center sills, a top cover-plate 4, and 55 a bottom cover-plate 5, thus constituting what is known as a "built-up" bolster; but a built-up bolster or a solid bolster will be used, in accordance with whether or not the center sills are continuous from end to end of the 60 car. There are no side sills in the preferred construction, and instead of end sills extending the width of the underframe there may be placed face-plates 6 over the ends of the center sills to receive the draw-bars, and the 65 face-plates at the ends of the center sills may be connected with the ends of the bolsters by means of diaphragms or beams 7, converging toward the center sills from the ends of the bolsters, and the ends may be covered over 70 with metal plates or flooring or other material for providing a suitable platform. As indicated in Figs. 2 and 3, the coupler-operating mechanism may be applied to one of these oblique sides of the platform. On that platform on which there is no brake-staff is provided a stanchion 8 for convenience of the trainman in going from one car to another.

The car-body, as already indicated, is substantially the contour of an inverted pyramid—that is to say, its longitudinal sides 9 converge, as also do its ends 10, and above the converging sides the walls of the body extend vertically, as at 11, and above the inclined ends the end walls 12 of the body also 80 extend vertically for any desired distance. Both the inclined and the vertical walls of the body may be of metal plates suitably united, as by riveting and, if desired, braced by vertical and diagonal braces, as shown 85 substantially in the right-hand half of Fig. 3. The truncated inverted apex of this inverted pyramidal body is supported above the center sills, and the sides are braced by gusset-plates 13 between bolsters, which gusset-plates are secured to the inclined sides and also secured to brackets 14, projecting laterally at intervals from the center sills.

These brackets 14 are secured to the center sills at points corresponding to the edges of the doors, and they are inclined on their upper faces to serve as supports for the doors 5 when opened and to render said doors serviceable as chutes for the discharge of the load. The inclined ends of the body are also supported and braced by longitudinal plate-struts 15, which may be stiffened by ribs 16, 10 and similarly-stiffened transverse plate-struts 17, interposed between and riveted to the underframe and said inclined ends. The vertical ends of the car are connected with the underframe by means of posts in any desired number, there being preferably, as 15 shown in Fig. 1, corner-posts 18 and intermediate posts 19, which may be secured to the underframe in any suitable way—as, for example, by means of angle-bars 20.

20 The doors, of which by preference there are four or two to a side, are designated 21, and they are hinged at 22 at their lower ends and open downwardly from above. Each door is provided with one or more brackets 25 23, connected with chains 24 on a winding-shaft 25, which winding-shaft may extend parallel with the inclined sides of the body and project beyond the ends thereof and have bearings in plates 26, erected between 30 the post 18 and 19 and there provided with any suitable actuating mechanism and detent or locking device, substantially such as shown in the right-hand side of Fig. 1.

The invention is not limited to the kind of 35 doors or door-operating mechanism shown, but what is shown is preferred.

The brackets 14, as already indicated, serve as bearings to receive the doors when they are opened, to support them at an incline to 40 the body, so as to constitute of them chutes to facilitate the side discharge of the load, and to take the strain off the operating chains or mechanism in the operation of unloading.

Since there are no side sills and the body 45 itself carries the load, it is evident that the body must be reinforced as well internally as externally, and, as already stated, external gusset-plates 13 are used to brace the body from the outside, and, as shown in Fig. 50 3, one or more internal gusset or partition plates 27 are employed, which extend vertically across the body from side to side. The vertical side walls may be reinforced by gusset-plates 28, connecting them with the top 55 edge of the gusset-plate 27. These several gusset-plates not only serve to tie the sides, but they also serve to keep the sides square and rigid. The external gusset-plates serve also as guides to prevent the discharging load 60 from running out behind the wheels.

Since there are no side sills and the load is practically carried by the body, or, more specifically, by the sides of the body, as already explained, it is apparent that the duty 65 of the center sills is largely that of taking up the end shocks.

By the cutting off of the platform or its formation with converging sides, as shown, the total light weight of the car is greatly reduced.

The push-pole pockets and car-steps may 70 be placed at the ends of the bolsters.

By the construction described there results in addition to the advantages already set forth the additional advantage that the load may be dumped very quickly, since the door-opening is large, and this further advantage growing out of the simplicity of the construction—namely, that repairs will be small and comparatively inexpensive.

Pressed steel or structural steel may be employed throughout, alone or together, as may be desired or found necessary or convenient.

While the car is primarily designed as an ore-car and the claims herein are so phrased, it is not thereby intended to limit the application of the car for that one purpose, and the claims are to be so understood. Where the car is constructed for use solely for ore and other granular freight, the doors at their meeting edges in the bottom of the body may 90 be provided with joints substantially like a piano-hinge joint or of other approved construction to avoid accumulation of the particles of the load in the joints.

What I claim is—

1. An ore-car, having an underframe without side sills, and comprising essentially center sills, bolsters, and end platforms having converging sides, and a body mounted above said underframe, and provided with outwardly and downwardly opening doors arranged between the bolsters. 95
2. An ore-car, having an underframe without side sills, and comprising essentially center sills, bolsters, and end platforms having converging sides, and a body mounted upon said underframe and arranged in such a way as to permit the dumping of the entire load either to one side or the other. 105
3. An ore-car, comprising an underframe, having center sills and bolsters, without side sills, and a superposed body of substantially the form of an inverted truncated pyramid, the inclined sides provided with outwardly and downwardly opening doors, means to open and close said doors, and means to support the doors in their open position. 110
4. An ore-car, comprising essentially an underframe, having center sills and bolsters, without side sills, a body mounted thereupon and having inwardly-inclined converging sides and ends, outwardly and downwardly opening doors arranged in pairs in opposite sides of the said body, door-operating mechanism extended to the ends of the body, and means to support the doors in their opened position. 120
5. In an ore-car, an underframe without side sills, and a body having downwardly-converging sides, and external and internal gusset-plates for reinforcing the sides. 130
6. In an ore-car, an underframe, having

center sills, and laterally-projecting brackets, combined with a body erected upon said underframe and having inclined sides, and gusset-plates interposed between said inclined sides and said brackets.

5 7. An underframe for cars, comprising center sills, bolsters and end platforms, said platforms consisting of sides converging from the bolsters to the center sills, a top floor.

10 8. An underframe for cars, comprising cen-

ter sills, bolsters and end platforms, said platforms consisting of sides converging from the bolsters to the center sills, a top floor, and push-pole pockets applied to the bolster ends.

In testimony whereof I have hereunto set 15
my hand this 24th day of May, A. D. 1902.

ARNOLD STUCKI.
